CLAIM

The ornamental design for a thin transparent cylindrical package, as shown and described.

DESCRIPTION

FIG. 1 is a perspective view of the thin transparent cylindrical package according to the invention;

FIG. 2 is a top view of the thin transparent cylindrical package as shown in FIG. 1;

FIG. 3 is a bottom view of the thin transparent cylindrical package as shown in FIG. 1; and,

FIG. 4 is a side view of the thin transparent cylindrical package as shown in FIG. 1.
